SHOE POLISH KIT

Robert V. Mathison, Box 730, Asheville, N.C.

Filed Sept. 21, 1962, Ser. No. 71,794

Term of patent 3½ years

(Cl. D9—2)

FIG. 1

FIG. 2

FIG. 3

FIG. 1 is a front perspective view of a shoe polish kit embodying my new design, illustrating the shoe polish kit in the closed position;

FIG. 2 is an exploded view thereof; and

FIG. 3 is another exploded view thereof.

The sides and ends not shown are substantially like the respective sides and ends shown. It is to be understood that the pad is continuous across the bottom of the polisher, as indicated in FIGS. 2 and 3.

I claim:

The ornamental design for a shoe polish kit, as shown and described.
